TABLE

John J. Lubberts and Lambert J. Mulder, Grand Rapids,
Mich., assignors to Tomlinson of High Point, High
Point, N.C., a corporation of North Carolina

Filed Oct. 26, 1959, Ser. No. 58,061

Term of patent 14 years

D33—14)

Fig. 1 is a perspective view of the table embodying our new design, and

Fig. 2 is an end view thereof.

The back of the table is substantially like the front of the table, and both ends of the table are substantially alike, one end of the table being shown in Fig. 2.

We claim:

The ornamental design for a table, substantially as shown and described.
